UNITED STATES PATENT OFFICE

WILLIS LERICHE, OF ALLENTOWN, PENNSYLVANIA, AND IRA V. BEASLEY, OF YUKON, OKLAHOMA, ASSIGNEES, BY MESNE ASSIGNMENTS, TO CANAL LINING COMPANY, INC., OF ALLENTOWN, PENNSYLVANIA, A CORPORATION OF NEW JERSEY

COMBINED DITCH PLOW AND GRADER

Application filed September 10, 1930. Serial No. 480,838.

This invention relates to ditching and grading apparatus and more particularly to a combined ditch plow and grader.

Although the device of the present invention may be used to advantage in different kinds of work, it is particularly adapted for use in making irrigation ditches or in clearing ditches previously in use. Usually, heretofore, such ditches have been unlined and, although the material at the sides and bottom of these ditches held the water reasonably well, there was a considerable loss of water due to seepage through the dirt or soil bounding the ditches.

It has been proposed to line such ditches with the usual poured concrete. This method of lining would require forms to hold the concrete in place while setting and it would require a considerable thickness of such material at the bottom of a ditch to avoid breakage when the bottom is subjected to the effect of substantial weight, as, for example, when one or more men get down into the ditch for cleaning or other purposes. The cost of lining ditches in this way would be prohibitive.

It has also been proposed to build ditches lined with gunite or the like formed of sand and cement projected into place against the dirt walls by means of a cement gun. Preferably the sides and bottom of ditch are shaped by suitable means so that the lower part of the contour of a cross-section will be substantially in the form of an arc of a circle and the inner surface of the ditch will have a sort of glaze due to the action of the shaping means, this glazed surface serving as a good backing against which the sand and hydrated cement are projected. With ditches lined in this way, satisfactory results may, due to various factors such as the inherent strength of the gunite, be made comparatively thin and at a relatively low cost. It is, however, important to provide means adapted for making ditches in such form that they can easily be rounded. Heretofore no satisfactory solution for this part of the problem has been found.

An important object of the present invention is to provide ditch making means adapted

to meet the aforesaid requirements. Another object is to provide an improved ditcher and grader. Further objects are to provide ditch making means adapted to form both sides of the ditch in the same manner simultaneously; 55 ditch making means adapted to raise dirt from the ditch at both sides and to move the dirt away from the ditch while at the same time leveling the dirt at the desired level; and ditch making means adjustable to determine the height of the side walls. 60

Other objects and advantages will appear upon consideration of the following detailed description and of the drawings in which:

Fig. 1 is a top plan view;

Fig. 2 is a view in side elevation with parts omitted and others broken away; and

Fig. 3 is a view in elevation, showing the ditcher and grader as seen from the rear.

Referring to the drawings, 1 is a drawbar 70 or beam, preferably in the form of a hollow metal beam of rectangular cross section, and 2 designates each of two plough shares attached to mould boards 3 which in turn are secured to the beam 1 by means including a 75 bar or support 4 extending downwardly and forwardly from the beam 1. At its forward end the beam 1 is provided with a clevis 6 for attachment to traction means, such as tractors, horses, etc. The clevis is connected 80 with the beam in any suitable manner, as by connecting means including a bolt 7 and a nut 8.

The depth of the cut by the plow may be regulated by means including an adjustable 85 guide shoe 9, preferably provided by bending back one end of a square rod or bar 10 to serve as the shoe, the rod 10 extending upwardly and rearwardly along one side of the beam 1 to which it is clamped by means of a 90 rod 11 bent around three sides of the beam 1, a plate 12 fitting over the threaded ends of the rod 11, and nuts 13 applied to said threaded ends.

Preferably the plough portion, to which 95 the description has been limited thus far, is provided with suitable handles 14, and, as shown in the drawings, they constitute the rear ends of the sides 15 of a triangular frame of which the vertex rests on the upper surface 100

of the beam 1 and the rear end is formed by a cross member 16 connected with the sides 15 at points adjacent to the handles 14. The triangular frame is supported at the rear of the vertex by suitable means, such as two pairs of braces 17 extending upwardly and rearwardly from the sides of the beam 1.

As shown in Fig. 1, the mould boards 3 are so formed as to force the dirt outwardly at both sides of the ditch at its top. However, the present invention contemplates not only the feature of forcing the loose dirt farther back from the sides of the ditch but also the feature of grading the loose dirt at a desired height above the bottom of the ditch. To this end, provision is made of two spreaders 18, each of which preferably includes a body portion 19 in the form of a steel plate, stiffeners in the form of angle irons 20 secured to the plate 19 along the inner face thereof and adjacent to its upper and lower edges, and a removable cutter 21 in the form of a steel plate demountably attached to the plate 19 by bolts 22 passing through the plate 19 and one flange of the lower stiffener 20, and nuts 23 screwed on the bolts.

In order to provide for varying degrees of spreading action and adjustment of the grade at the sides of the ditch with reference to the bottom of the ditch, the connections between the two spreaders themselves and between the spreaders and the plow portion of the apparatus must be such that the angle between the spreaders may be varied and they may be connected with said plow portion at different heights. According to the embodiment disclosed herewith, the body portion 19 of each spreader is provided at its forward end with an eye 24, secured thereto as by welding, and each eye 24 is mounted on a guide or hinge bar 25 at the corresponding side of the apparatus. Preferably these so-called hinge bars 25 are the legs of a U-shaped member and are connected at their upper ends with the corresponding sides 15 of the triangular frame carrying the handles 14. The desired vertical adjustment of the forward end of each spreader may be maintained by means of a set screw 26a threaded through the side of the corresponding eye 24 so that it may be tightened against the corresponding hinge bar or member.

Also the spreaders must be strongly as well as adjustably supported at their inner sides. For this purpose, there are provided, according to the present embodiment of the invention, an adjustable brace 26 connecting the spreaders near their rear ends and pivotally attached thereto and two inclined adjustable braces 27, each pivotally connected at one end with the front end of one of the spreaders and at the other end with the other spreader at a point farther to the rear. As here disclosed, the braces 26 and 27 are telescopic and are of the pipe and bar type, that

is one section 28 of each of these braces is in the form of a pipe and the other section 29 is in the form of a bar slidably mounted in the pipe. Each of these pipes and bars is provided at its outer end with an eye 30 receiving a vertical pivot formed by the shank of a bolt 31 passing through flanges 32 of the stiffeners 20 and secured in position by nuts 33.

The sections 28 and 29 of the adjustable braces may be held in adjusted position with respect to each other by pins 28a inserted into holes 29a in the pipe sections and 29b in the bar sections. These eyes 30 do not occupy the entire length of the shanks between the pairs of stiffeners but they may be held against movement along the shanks by means including brackets 34 secured to the outer ends of the braces and engaging the inner faces of the projecting flanges of the stiffeners 20. Preferably the brackets 34 are formed with openings to receive the shanks of the bolts 31, thus providing, in effect, longer bearing connections between the braces and the bolts.

It will be evident that, in addition to the connection of the forward ends of the spreaders 18 with the hinge bars 25, there should be provision for support of the spreaders to the rear of said hinge bars. To this end, the beam 1 may be provided with a rearward extension 35 (here shown as a beam or member of which one end is inserted in the rear end of the hollow beam) and the spreaders may be supported from this extension by suitable means such as a flexible connector 36 connecting the brace 26 with said extension 35. The length of the connection between the brace 26 and the extension 35 may be varied in accordance with the vertical adjustment of the spreaders along the hinge bars. After adjusting the spreaders at the proper height, the parts may be retained in adjusted position by tightening the set screws 26a and securing together the ends of the connector 36 by suitable means such as a clamp 37 including two parts 38 and 39 with corresponding grooves to receive the ends of the connector and a screw 40 positioned between the sets of grooves and adapted to draw the parts together to clamp the ends of the connector or to release them in accordance with the direction of the rotation of the screw.

Upon inspection of the drawings, it will be seen that the plow is broad at its base and will form a ditch or trench of the general form desired. Also the shares and mould boards at opposite sides of the plow are symmetrical with respect to a vertical plane passing through the axis of the beam 1, and consequently the opposite sides of the ditch are symmetrical with respect to each other.

It will be apparent that the apparatus of this invention is particularly adapted for cutting a ditch which can readily be trimmed

to provide a cross-section in the general form of a segment of a circle, and for spreading and leveling the material thrown up from the ditch.

5 It should be understood that various changes may be made in the construction and arrangement of parts and that parts may be used without others without departing from the true spirit and scope of the invention.

10 Having thus described our invention, we claim:

1. In a device of the character described, a beam, mould boards below said beam and arranged to act equally on opposite sides thereof, said mould boards being rigidly connected with the beam, two vertical hinge bars rigidly connected with said beam and arranged with one back of each of the mould boards and adjacent to the rear surface thereof, a spreader hinged on each of said hinge bars and movable upwardly and downwardly thereon, means for adjusting the angle between the spreaders, and means for holding the spreaders at any desired height.

25 2. In a device of the character described, a beam, mould boards below said beam and arranged to act equally on opposite sides thereof, said mould boards being rigidly connected with the beam, a spreader back of each 30 of the mould boards, a hinge at the forward end of each of said spreaders limiting it to swinging movement about a vertical axis fixed with respect to the beam and to upward and downward movement, means including 35 adjustable braces for adjusting the angle between said spreaders, and means for holding the spreaders at any desired height.

3. In a device of the character described, a beam, mould boards below said beam and arranged to act equally on opposite sides of the beam, said mould boards being rigidly connected with the beam, a U-shaped member having as its legs substantially vertical hinge bars rigidly connected at their upper ends 45 with said beam and arranged back of the mould boards and adjacent to the rear surface thereof, a spreader for each side of the device, hinged to the corresponding hinge bar and movable upwardly and downwardly 50 thereon, and means for maintaining the spreaders in adjusted position.

4. In a combined ditch plow and grader as described, a metal beam, mould boards below said beam and arranged to act equally on opposite sides of the beam to shape the ditch and raise the loosened dirt above the top of a ditch, means for rigidly connecting said mould boards with said beam including a member integral with the beam at its upper end and extending downwardly and forwardly at the line of connection between the forward edges of the mould boards, a vertical hinge bar rigidly connected with said beam adjacent the back of each of the mould boards, a spreader hinged on each of said

hinge bars and movable upwardly and downwardly thereon, means for adjusting the angle between the spreaders, and means for holding the spreaders at any desired height.

5. In a combined ditch plow and grader, a 70 metal beam, mould boards below said beam and acting equally on opposite sides thereof, said mould boards being rigidly connected with the beam, a V-shaped member of which the vertex engages the top of the beam and 75 the sides constitute handles, means for rigidly connecting said V-shaped member with said beam, a U-shaped member of which the uprights are adjacent to the back of the corresponding mould boards and constitute 80 hinge bars of which the upper ends are integral with the corresponding handles, a spreader on each of said hinge bars and movable upwardly and downwardly thereon, means for adjusting the angle between the 85 spreaders and means for holding the spreaders at any desired height.

In testimony whereof we affix our signatures.
